Attorneys.

UNITED STATES PATENT OFFICE.

JOHN L. L. KROOK, OF PROCTOR, VERMONT, (NOW DECEASED AND BY DECREE OF DISTRIBUTION TO A. ELIZABETH KROOK.)

RIVETING-MACHINE.

1,375,395.

Specification of Letters Patent. Patented Apr. 19, 1921.

Application filed August 12, 1918. Serial No. 249,456.

To all whom it may concern:

Be it known that I, JOHN L. L. KROOK, a citizen of the United States, residing at Proctor, in the county of Rutland and State 5 of Vermont, have invented or discovered certain new and useful Improvements in Riveting-Machines, of which the following is a specification, reference being had therein to the accompanying drawing.

10 This invention relates to a riveting machine or device which is of simple construction and by means of which riveting operations can be effected either manually or by power.

15 In the accompanying drawing Figure 1 is a side view, partly in section, illustrating the improved riveting machine or device and its method of operation. Fig. 2 is a front end view of the same.

20 Referring to the drawing, 12 denotes a bar having a head portion 13 to which is jointed, by means of a pin 14, the upper ends of links 15 jointed at their lower ends, by means of pins 16, to a fork 17^a at the 25 forward end of a lever 17. The head 13 is provided with a recess for the reception of a sliding pin or plunger 18 carrying at its lower end a riveting block 19 to which the fork 17^a is jointed by a pin 20. The riveting block 19 has a concave recess in its lower 30 end adapted to properly upset the metal of the rivets to form rivet heads. The head 13 is preferably provided with an oil hole 43.

35 Attached to the bar 12, preferably by a set screw 40, permitting adjustment, is a steady bar 21 having a shank portion 22 adapted to be inserted through holes 37 in plates 38 or the like which are to be riveted 40 together. The shank portion 22 of the bar 21 passes through a hole in a resistance bar 23 to which is pivoted, by a pin 41, a locking lever 24 having a projection or nose portion 25 adapted to be received in any one 45 of a series of notches 26 in the lower part of said shank 22. The hole in the resistance bar through which the shank 22 passes is preferably somewhat flaring upwardly, as shown, for the easy insertion of said shank, 50 and the surface 42 on the bar 23 against which the rounded upper end of the lever 24 works is preferably in the arc of a circle of which the pin 41 is the center so that no pressure on said bar will release the locking 55 lever 24.

A suitable spring, herein shown as a coil spring 27, serves to yieldingly retain the projection 25 in a notch 26 in which said projection may be entered. Adjustably attached, as by a set screw 39, to the bar 23, is 60 a riveting block 28 having a concave recess to receive a previously formed head 29 of a rivet 30.

Adjustably attached to the supporting bar 12 is a steady device coöoperating 65 with the steady bar 21 and preferably consisting of a steady and spacing pin 31, said pin being threaded for the reception of nuts 32 and 33 by which it is fixed in place on the said bar 12, the latter being 70 provided with a slot 34 permitting an adjustment of the said pin. The spacing pin 31 passes through holes 37 in the plates 38 to be riveted together and abuts against the bar 23, said bar being preferably provided 75 with a slot 35 by which said pin is steadied in place in different positions of adjustment of the block 12. By adjusting the riveting block 28, and correspondingly adjusting the spacing pin 31, the machine will be adapted 80 for operation with plates or the like which are to be riveted together and which have differently spaced holes. The steady and spacing pin 31 need not necessarily enter holes in the work, and the machine might 85 be properly steadied by other means, co-operating with the bar 21, than said pin, as for example, by making the nut 32 on the pin 31 long enough to directly engage the work.

To avoid a shearing strain on the pins 14, 16 and 20 the head 13 is preferably provided with shoulders 13^a against which the rounded upper ends of the links 15 work, and the fork 17^a is also preferably provided with 95 shoulders 17^b against which the rounded lower ends of said links work. Also the block 19 is preferably formed with shoulders 19^a against which the rounded front end portions of the fork 17^a work.

From the foregoing it will be understood that the links 15 and the coöoperating forward end or yoked portion 17^a of the lever 17 afford a toggle device of great power, so that when the said lever 17 is lifted, either 105 manually or by power, the toggle will be straightened and the riveting block 19 will be forced down against a rivet so as to upset the same and form a second rivet head 36. When this riveting operation has been 110

performed the locking lever 24 may be released from the shank 22 of the bar 21, and said bar and the spacing pin 31 may be withdrawn from the previously formed 5 holes 37 in the plates 38, and the riveting device may then be adjusted to a new position relative to said plates for a new riveting operation.

While I have herein shown and described a 10 preferred form of my invention the said invention is not to be understood as being limited to the particular form thereof, or to the details of construction, herein set forth; a leading feature of my invention residing 15 in the means whereby the machine may be properly mounted in place in the work in such a manner as to set the rivets in differently spaced rivet holes, and this feature may be used in connection with different 20 means than the toggle device for operating the movable riveting block 19 herein set forth; as, for example, by hydraulic pressure applied to the pin or plunger 18. As hereinbefore stated the operating lever 17 25 may be actuated manually or by power applied in any suitable manner, and this might include the use of hydraulic or pneumatic power-applying devices. The pin 20 is preferably made removable so that interchangeable riveting blocks 19, as well as 28, having cavities for differently shaped rivet 30 heads may be employed.

It will of course be understood that the 35 invention is intended to be used with red hot rivets as is common in riveting machines, and it will also be understood that the special toggle device herein shown and described, and having bracing shoulders to relieve the pins of the toggle joints from 40 shearing strains, may be used in any kind of a riveting machine.

Having thus described my invention I 45 claim and desire to secure by Letters Patent:

1. A riveting machine or device comprising the combination with a supporting bar having a recessed part, of toggle links jointed to said bar adjacent said recessed part, 50 a pin or plunger working in said recessed part and carrying a riveting block, a forked lever to which said links are jointed and the forked forward toggle part of which lever has jointed connections with said riveting block, a resistance bar provided with an aperture, a second riveting block attached to said resistance bar, a steady bar attached to said supporting bar, locking means for said steady bar, and additional steady means attached to said supporting bar.

2. A riveting machine or device comprising the combination with a supporting bar having a recessed part, of toggle links joint-

ed to said bar adjacent said recessed part, 65 a pin or plunger working in said recessed part and carrying a riveting block, a forked lever to which said links are jointed and the forked toggle part of which lever has jointed connections with said riveting block, a resistance bar provided with an aperture, a second riveting block adjustably attached to 70 said resistance bar, a steady bar attached to said supporting bar and having a shank passing through said resistance bar, locking means for said steady bar, and a steady pin adjustably attached to said supporting bar at a distance from said steady bar.

3. A riveting machine or device comprising the combination with a supporting bar having a recessed part, of toggle links jointed to said bar adjacent said recessed part, 75 a pin or plunger working in said recessed part and carrying a riveting block, a forked lever to which said links are jointed and the forked toggle part of which lever has jointed connections with said riveting block, a resistance bar provided with an aperture, a second riveting block attached to said resistance bar, a steady bar attached to 80 said supporting bar and having a shank passing through said resistance bar, a spring-pressed lever for locking said steady bar, and a steady pin attached to said supporting bar at a distance from said steady bar.

4. In a riveting machine or device, the 85 combination with a supporting bar and a resistance bar, of properly mounted opposing riveting blocks, one of which is movable and the other of which is fixed to said resistance bar, means for operating said movable riveting block, and means for holding 90 the riveting machine in place on the work for riveting operations, said holding means comprising a plurality of pins attached to said holding bar and adapted to pass through rivet holes in the work and engage 95 said resistance bar, one of said pins being adjustably mounted on said holding bar and said fixed riveting block being adjustably mounted on said resistance bar.

5. In a riveting machine, the combination 100 with fixed and movable riveting blocks and a stationary head, said head and said movable riveting block having shoulders, a toggle device comprising a fork having shoulders, links pivoted to said head and fork 105 and having rounded ends working against said shoulders on said head and fork, said fork having rounded ends working against said shoulders on said riveting block, said shoulders preventing shearing strains on the 110 toggle pivot pins.

In testimony whereof I affix my signature.
JOHN L. L. KROOK.
